LIQUID-DISPENSING APPARATUS

Edwin P. Sundholm, Albert City, Iowa

Application March 21, 1941, Serial No. 384,462

6 Claims. (Cl. 221—85)

The present invention relates to liquid-dispensing apparatus in general, and it relates more particularly to pumping apparatus adapted for attachment to drums or barrels or like reservoirs containing various liquids, as for example gasolines, alcohols, kerosenes, light or heavy lubricating or fuel oils of varying viscosities or other liquid substances, said pumping apparatus thereafter being operable to dispense as much or as little of the liquid contents of said reservoir as desired.

One of the objects of the present invention is to provide durable low-cost pumping apparatus, of simple construction and high capacity, having new and improved features of construction and arrangements of parts affording many advantages, both from the standpoint of ease of assembly and disassembly of the component parts with respect to each other and with respect to the reservoir whose contents are to be dispensed, as well as from the standpoint of operating efficiency during actual use.

Other objects will appear more fully from the following detailed description, accompanying drawings and appended claims.

For the purpose of illustrating the invention, there is shown in the accompanying drawings forms thereof which are at present preferred, since the same have been found in practice to give satisfactory and reliable results, although it is to be understood that the various instrumentalities of which the invention consists can be variously arranged and organized and that the invention is not limited to the precise arrangements and organizations of instrumentalities as herein shown and described.

Referring to the drawings, wherein like reference characters indicate like parts,

Figure 1 represents a perspective view of pumping apparatus constituting one embodiment of the present invention shown operatively engaged with a metal drum filled with liquid, said drum having a portion of its side wall broken away to reveal the lower telescopicable pump inlet stem portion of said apparatus.

Figure 2 represents an enlarged fragmentary longitudinal sectional view taken through that portion of the pumping apparatus shown in Figure 1 which extends above the top end wall of the drum.

Figure 3 represents an enlarged side elevational view of the top right side of the apparatus illustrated in Figures 1 and 2, such as would be seen for example on broken line 3—3 of Figure 2, looking in the direction of the arrows.

Figure 4 represents an enlarged fragmentary longitudinal sectional view taken through the lower portion of the pumping apparatus illustrated in Figure 1.

5 Figure 5 represents a fragmentary view in perspective of the lowermost telescopicable inlet end portion of the pumping apparatus illustrated in Figures 1 and 4, with a portion of outermost tubular side wall being broken away to reveal underlying details of construction.

10 Figure 6 represents a transverse sectional view through the cylinder portion of the pumping apparatus looking upwardly at the slideable apertured piston, such as would be seen for example on line 6—6 of Figure 4, looking in the direction of the arrows.

15 Figure 7 represents a transverse sectional view through the drum-engaging fitting at the lower end of the pump barrel, looking upwardly at the check-valve housed therein, as for example on line 7—7 of Figure 4, looking in the direction of the arrows.

20 Figure 8 represents an exploded view in perspective of the elements constituting the movable portion of the check-valve illustrated in Figure 4, as they appear before assembly.

25 Figure 9 represents a perspective view of modified fittings made from steel stampings, which may replace the cast metal fittings at the upper and lower ends of the pump cylinder shown in the preceding figures—portions of the fittings being broken away to reveal details of construction, and the intervening pump barrel being indicated in phantom fashion by dashed-dotted lines.

30 35 Figure 10 represents a perspective view of the steel stampings 110 and 111 as they appear when dis-assembled and showing a means for providing a vent opening alternative to that shown in Figure 9.

40 45 Figure 11 represents an enlarged, fragmentary, cross-sectional view of the inner and outer tubes 89 and 90 showing another method of forming a packing seal therebetween, alternative to that shown in Figures 4 and 5.

50 55 Figure 12 represents a view similar to that of Figure 11 showing another method for providing a packing seal—the packing being self-adjusting to maintain a tight seal.

Figure 13 represents a fragmentary, perspective view of the embodiment shown in Figure 11—the parts being dis-assembled.

Figure 14 represents a fragmentary perspective view of the embodiment shown in Figure 12—the parts being dis-assembled.

In Figure 1 of the accompanying drawings,

pumping apparatus constituting one illustrative embodiment of the present invention is shown operatively engaged with an upright cylindrical liquid-containing steel barrel or drum, indicated generally by the numeral 20. This liquid-containing barrel or drum 20 may be of any suitable shape and size, and of any suitable construction, one form of which has been illustrated in Figure 1. This illustrated drum is formed from relatively thin sheet steel, and includes a cylindrical body portion 21 having circular upper and lower ends 22 and 23 respectively secured in fluid-tight relation to the opposite end portions of said body 21. The upper drum end 22 bears at least one internally-threaded bung-receiving hole 24, which is normally closed when the barrel is in storage or in transit prior to use by any suitable externally-threaded bung or closure plug.

The drum 20 may be readily prepared for dispensing by merely standing it on one end with the bung-end 22 uppermost and then unscrewing the bung from the hole 24, whereupon the pumping apparatus of the present invention may be readily and easily attached to the drum by merely screw-threadedly engaging it with the internally-threaded bung-hole 24, in the manner to be described more particularly hereinafter.

The dispensing apparatus illustrated in Figures 1 to 8 inclusive, constituting one illustrative embodiment of the present invention, includes an upright preferably steel pump cylinder 25, of relatively substantial internal diameter bearing at its upper end a spout-bearing cast-metal fitting 26, and having its lower end screwed into a stepped cast-metal drum-engaging fitting 27 adapted for screw-threaded engagement with the internally-threaded bung-hole 24 of the liquid-containing drum or reservoir 20.

As more particularly illustrated in Figure 2, the upper spout-bearing cast fitting 26 includes a central dome-like portion 28 having an internally-threaded opening 29 at its lower end adapted screw-threadedly to receive the externally-threaded upper end of the cylinder 25, and also preferably includes an internal annular gasket-seat 30 disposed immediately above the lowermost opening 29 for receiving the gasket 31. When engaged, the upper end of the cylinder 25 abuts against the snugly-seated gasket 31, thereby insuring a fluid-tight seal between cylinder and fitting.

An arched discharge spout portion 32 of the general configuration illustrated in Figures 1 and 2 may be formed integrally with and extend from the central domed portion 28 of the upper fitting 26, or else this spout portion 32 may be formed separately therefrom and then suitably permanently secured thereto, by welding or otherwise, with its internal passageway 33 in communication with the interior of said central domed portion 28. In the preferred embodiment, the discharge end of the spout 32 is preferably disposed at a higher elevation than the inlet end, which is itself disposed a substantial distance above the top drum end 22 by reason of the intervening cylinder 25. This arrangement permits a receiving vessel of substantial height and capacity, as for instance a five-gallon container 34, to be set down on the drum head 22 directly under the discharge end of the spout 32, and be filled with liquid pumped from the larger drum 20 without any waste whatsoever, and with dispatch.

The discharge end portion of the spout 32 may

be provided with an outwardly and upwardly inclined boss or hook 35 over which the bail of a receiving vessel may be placed, so that the vessel may be suspended from the spout in operative relation thereto and filled without waste.

The extreme end portion of the spout 32 may also bear an external screw-thread 36 for connection with a hose end-coupling 37, so that the liquid dispensed may be conducted by the flexible hose 38 directly into a receiving-vessel or chamber remote from the dispensing apparatus, as for example directly into the fuel-tank of a tractor, or the like.

The upper end of the dome 28 bears a hollow cylindrical guide-stem 39 through which slidably extends a piston-rod 40, preferably of steel, having its lower end attached to the piston 41 inside the cylinder 25. The upper end 42 of the rod passageway through the stem 39 is countersunk so as to guide the annular piston-rod packing 43, which may be impregnated with graphite, into closer and more intimate contact with the reciprocable piston-rod 40 when thrust axially downwardly by the externally-knurled nut 44 which screw-threadedly engages with the stem 39.

The piston rod 40 may be reciprocated manually, or it may be motor-actuated. In the particular embodiment illustrated in Figures 1, 2 and 3, the piston rod 40 is manually actuatable by a hand lever 45 pivotally connected at its one end to the upper end of the piston-rod 40 and pivotally connected to an intermediate point to the upper end of a link 46, whose lower end is pivotally secured to an outwardly extending boss 47 which may either be formed integrally with, or separately from and permanently secured to, the head-fitting 26.

As more particularly illustrated in Figure 3, the lever 45 may be constructed from two juxtaposed metal bars 48 and 49 of rectangular cross-section, having divergent end portions adjacent the piston-rod 40 providing the illustrated bifurcated arrangement which straddles said piston-rod, and which may be pinned thereto by a headed pivot pin 50 secured against removal by the cotter pin 51. The other end of the lever 45 may extend into a hollow handle 52, which may be formed from two juxtaposed concave shells 53 of oval-shaped contour, spot-welded to the inwardly-extending handle at recesses 54, and whose forward end portions may be riveted to the handle at 55.

The link 46 which connects the handle 45 to the head-fitting 26 may be constructed from two juxtaposed metal bars 56 and 57, whose upper ends embrace the handle 45 and are pinned thereto by the pivot pin 58, and whose lower ends straddle the upper end of the boss 47 and are pivotally secured thereto by the pivot pin 59.

If desired, however, in lieu of the hereinabove-described lever arrangement for manually actuating the piston rod 40, the upper end of said piston-rod may bear a cross-piece or T shaped handle 60 like that illustrated in Figure 9, which may be grasped by the operator and alternately pulled and pushed to reciprocate the piston-rod 40.

To the lower end of the piston-rod 40 may be secured a shallow cup-like metal piston 41, which may be pressed out of a flat sheet-steel disc, with its periphery bent upwardly to provide an annular web of metal 61 of limited axial extent paralleling the cylindrical side-wall of the pump-cylinder 25. The outside diameter of this upturned marginal portion 61 is preferably some-

75

what smaller than the inside diameter of the steel cylinder 25, so as to leave a slight gap between these two elements. The outer surface of the upturned marginal portion 61 bears an annular groove of rectangular cross-section, and in this groove is disposed a narrow trans-split piston-ring 62, also of rectangular cross-section, preferably constructed from brass, although if desired it may be constructed from other material. This piston-ring 62 is closely fitted to the side-wall of the cylinder 25, and is spring-tempered, and continuously exerts outward radial pressure against said cylinder wall, thereby providing an effective fluid-tight seal between the piston and the cylinder, and at the same time affording minimum frictional resistance during piston travel. The axial width of the piston-ring 62 is preferably slightly less than that of the ring-groove, so as to provide slight clearance, permitting the ring to flex radially inwardly or outwardly when necessary without interference from the side-walls of said groove.

The piston 41 may be secured to the rod 40 in any suitable manner, as for instance by having the lower end portion of the piston-rod 40 reduced in diameter and extended through a central hole in the piston, and upset on the underside of the piston to form the head 63.

As more particularly illustrated in Figures 4 and 6, the flat central zone of the piston 41 bears a plurality of apertures 64, through which liquid trapped in the pump cylinder 25 below said piston passes upwardly on the down-stroke of the piston. Immediately above and completely covering these piston-apertures 64 is disposed a preferably light-weight valve disc 65, of outer diameter sufficiently smaller than the inside diameter of the piston marginal portion 61 to permit said disc 65 to seat itself snugly against the aperture-bearing flat central zone of the piston 41. This valve disc 65 is loosely slidably mounted on a piston-rod portion 66 of reduced diameter disposed immediately adjacent the piston 41.

In actual operation, assuming the piston 41 to be starting its down-stroke, and further assuming the space in the pump cylinder 25 below said piston to be filled with liquid trapped therein by valve-means in the lower fitting 27, which means will be described in detail hereinafter, the pressure of said liquid in the cylinder 25 is communicated upwardly through the piston apertures 64 to the underside of the light-weight valve disc 65, unseating the valve disc and sliding it upwardly to the stop shoulder 67 which defines the upper limit of the piston rod portion 66 of reduced diameter. This leaves the piston apertures 64 unobstructed, permitting the piston 41 to descend freely and rapidly through the body of trapped liquid in the cylinder 25, said liquid meanwhile flowing upwardly through the descending apertures 64 and passing to the upper side of the piston, as indicated by the curved arrows in Figure 4.

At the end of the piston down-stroke, the valve disc 65 seats on the piston 41 over the piston openings 65, and when the piston ascends, the weight of the column of liquid above the piston holds the disc valve 65 firmly down against the piston as illustrated in Figure 2, thereby firmly closing the openings 64 and preventing escape of liquid downwardly therethrough as the piston ascends.

The ascending piston 41 lifts the liquid above it and discharges it through the head fitting 26 and discharge spout passageway 33.

The lower end zone of the cylinder 25 is externally-threaded and is screwed into the fitting 27 which is engaged with the drum 28. If desired, the very lowermost extremity of the cylinder 25 may be marginally inturned to some slight extent, as illustrated in Figure 4. The upper outer portion of the fitting 27 is polygonal-shaped as at 68, to permit a wrench or other suitable turning tool to be applied thereto for the purpose of screwing the fitting tightly into, or loosening it with respect to, the threaded drum bung-opening 24. The fitting 27 may be threaded externally below the polygonal portion 68 for direct screw-threaded engagement with the threaded bung-holes of various drums. Thus, for example, the zone 69 immediately below the polygonal portion 68 may be threaded for engagement with a bung-hole of any standard size as for instance a two-inch bung-hole, and immediately below this threaded portion 69 may be provided a second threaded portion 70 of reduced diameter for engagement with a standard bung-hole of smaller size, as for instance, a one and a half inch bung-hole. The particular diameters of these externally threaded portions of the fitting 27 may be chosen to suit individual requirements, and although two threaded portions of different diameters have been illustrated, it is to be expressly understood that more or less than two threaded portions may be provided. This arrangement whereby the pumping apparatus is screwed directly into the bung-hole of the reservoir prevents any possible seepage of rain water or entry of dirt into the reservoir.

As more particularly illustrated in Figure 4, a suction valve of novel and inexpensive construction is housed inside the fitting 21 in operative proximity to the lower end of cylinder 25. This suction valve includes a relatively fixed body portion 71, and a relatively movable valve portion 72. The fixed portion 71 may be stamped out of a steel disc, with its central portion being depressed to provide the frusto-conical downwardly-depending portion 73, whose walls bear a plurality of openings 74 through which fluid may pass on its way up into the pump cylinder 25. The rim portion of the valve body 71 is preferably flat, and may rest between annular sealing members 75 compressed between the lowermost extremity of the cylinder 25 and the juxtaposed internal shoulder 76 in the fitting 21.

The movable portion 72 of the suction-valve includes a vertical stem 77 which passes with ample clearance through the hole centrally disposed in the lower extremity of the valve body depression 73. The stem 77 has a headed upper end portion 78, originally of reduced diameter, which extends through and holds together a pair of juxtaposed clamping-plates 79 and 80. The uppermost plate 79 is generally flat throughout its central portion, with its margin being inclined first upwardly and then downwardly to form on the underside thereof an annular V-shaped trough having angularly-related side walls. The lowermost plate 80 is also generally flat throughout its central portion, and has its marginal portion downturned in approximate parallelism with the outermost downturned marginal portion of the upper plate 79. Intermediate the marginal portions of these two juxtaposed plates 79 and 80 is disposed an annular sealing member 81, preferably constructed from cork, although other suitable materials may also be employed. As illustrated in Figure 8, this sealing member 81 is of generally rectangular cross section prior to

assembly, but when the innermost peripheral portion of this sealing ring 81 has been seized between and operatively pressed by the marginal portions of the juxtaposed clamping-plates 79 and 80, the resilient member 81 is deformed with its outermost periphery assuming a somewhat spherical surface which is admirably adapted for sealing engagement with the annularly-continuous concavely-conical surface at the base of the depressed body portion 78.

The valve stem 77 is constantly urged downwardly by a conical valve spring 82 interposed between the lowermost end of the valve body 73 and a cotter pin 83 extending through a suitable transverse hole in the lower end of the valve stem. The individual coils of the valve spring 82 may be so arranged as to all lie in the same plane when the spring is sufficiently compressed. The thrust exerted by this valve spring 82 constantly urges the outer surface of the cork sealing ring 81 into intimate sealing contact with the concavely-conical inner surface at the base of the depressed body portion 78, and the movable valve-assembly 72 being free to adjust itself relative to the body 71 by moving sideways or even tilting slightly if necessary, the cork ring 81 will find the best and most snug seat available, under the influence of this valve spring 82.

In actual operation, the upstroke of the piston 41 creates suction on the upper side of the valve 72, which is amply sufficient to overcome the relatively slight downward force exerted by the valve-spring 82, and lifts the valve upwardly, sucking liquid from the reservoir up through the pump inlet stem and through the valve-body openings 74 and past the unseated cork ring 81 up into the pump cylinder 25. When the piston 41 ceases to move upwardly, the valve-spring 82 seats the valve ring 81 snugly against the valve seat, thereby trapping the fluid which has already passed upwardly through the valve. The hereinabove-described suction valve is highly efficient in actual operation, and will seat properly regardless of the consistency or viscosity of the liquid being pumped, and will keep the pump-cylinder 25 primed continuously and will not permit it to lose its charge.

A venting passageway 84 extends through the side wall of the fitting 27, its function being to maintain constant atmospheric pressure inside the steel drum 28 as the liquid contents thereof are depleted. In the embodiment illustrated in Figure 4, this vent passageway 84 includes a vertical branch 85 drilled downwardly through the wall of the fitting, and a communicating inclined passageway 86 drilled upwardly through the stepped side-wall portion of said fitting. Where necessary, the fitting wall in the zone of the vent passageway may be somewhat thickened as at 87, to provide the necessary structural strength and to provide sufficient thickness of metal to accommodate the passageway.

The provision of the vent passageway as an integral part of the pumping apparatus of the present invention obviates the need for removing a second bung, where provided, to vent the inside of the drum or reservoir, and makes possible the efficient dispensing of the contents of drums or reservoirs which are supplied with only one bung opening. Furthermore, the location of the upper end of the vent passageway at an elevation substantially higher than that of the adjacent reservoir panel 22, and the absence of any flat surface of substantial area at said upper end of said vent passageway, prevents rain water or

particles of dirt or foreign matter which might collect on said adjacent drum panel or flat surface from entering the drum or reservoir through said vent passageway and contaminating the liquid contents thereof.

The lowermost end of the fitting 27 is provided with an internally-threaded opening 88 into which may be screwed the upper end of a telescoping extensible pump inlet-stem arrangement. This inlet-stem arrangement may include a relatively fixed tube 89 whose upper end is screwed into said fitting opening 88, and whose lower end portion may be telescoped into an outer tube 90 of slightly larger internal diameter. The lower extremity of the outer tube 90 is adapted to rest directly on the drum bottom 28, and the lower side-wall portions of said tube bear notches 91 which permit the liquid at the bottom of the drum to flow freely into said tube.

As more particularly illustrated in Figures 4 and 5 of the accompanying drawings, an annular packing ring 92, which may be formed of cork or any other suitable material, is interposed between the telescoping inner and outer tubes 89 and 90, and seals the joint therebetween. This packing ring 92 may be of rectangular cross section, and may extend into an annular groove 93 formed near the lower end of the upper tube 89. If desired, the packing ring 92 may be trans-split, with the plane of the cut being non-parallel with the center axis of said ring, and not intersecting said axis within the confines of the overall outline of said ring.

In place of the arrangement shown in Figures 4 and 5 for forming a seal between the inner and outer tubes 89 and 90, there may be used the arrangement shown in Figures 11 and 13. In this embodiment, the lower end of the tube 89 is turned down as at 121 so that it has a smaller outside diameter than has the rest of the tube 89. The lower portion of the turned-down end 121 is externally threaded as at 122.

About the upper, un-threaded portion of the end 121 are placed upper and lower steel washers 123 and 124 respectively, and an intermediate, continuous ring of cork, felt or other kind of pliable packing 125. A nut 126 is then screwed on to the threaded portion 122 thereby to compress said packing 125 in an axial direction and correspondingly to expand said packing 125 radially outwardly. This radially outward expansion causes said packing to provide a fluid-tight seal between the inner tube 89 and the outer tube 90.

As said packing 125 becomes worn from use, it may be adjusted simply by further tightening the nut 126 to provide additional expansion and thereby again to form a fluid-tight seal.

I may also provide the sealing arrangement shown in Figures 12 and 14. In this embodiment the lower end of the inner tube 89 is reduced or turned down as at 127 to provide a cylindrical portion having a smaller outside diameter than that of the remainder of the tube 89. A steel wedge collar 128 is provided with an inside diameter corresponding to the outside diameter of the turned-down portion 127 and a frusto-conical, outer surface 129, said outer surface terminating in an annular, outwardly-extending flange 130 at the lowermost portion of said collar 128.

This collar 128 is more or less permanently fitted about the turned-down portion 127 by any appropriate means, as for example by pressing said collar 128 on to said portion 127.

Somewhat above the turned-down portion 127 an outward annular extension 131 is formed in the tube 89. This extension may be pressed out of the pipe 88 or said extension 131 may be formed by securing (by spot-welding, soldering or other appropriate means) a separate, annular member about the tube 89. Instead of having an annular, outward extension, as shown in Figures 12 and 14, it is also possible to provide one or more knobs or extensions circumferentially disposed about said tube 89—the function of the extension 131 being merely to provide an abutment for a coil spring 132 to be hereinafter described.

I may provide upper and lower, annular steel washers 133 and 134 respectively. I prefer to have the outside diameter of said washers approximately the same while having the inside diameter of the lower washer 134 greater than the inside diameter of the upper washer 133—the inside diameter of said lower washer 134 being greater than the maximum outer diameter of the frusto-conical surface 129 of the collar 128.

Between said upper and lower washers 133 and 134, I provide a continuous ring of cork, felt or other kind of pliable packing 135 which has a vertical outer surface 136 and an inclined inner surface 137—said inner surface 137 being formed at generally the same angle as the outer surface 129 of the wedge collar 128. A coil spring 132 is disposed intermediate the upper washer 133 and the extension 131 on the tube 89 and urges the packing assembly downwardly over the outer surface 129 of the collar 128. The inclined surface 129 produces a camming action upon the packing 135 under the influence of the spring 132 so that said packing 135 is given a radially-outward component.

Thus, the spring 132 urges said packing 135 continuously radially outwardly and into contact with the inner surface of the outer tube 90. As the packing 135 becomes worn about its outer periphery, the spring 132 will expand further to force said packing 135 downwardly (upon the surface 129 of the collar 128) and consequently radially outwardly to maintain a fluid-tight seal between said inner and outer tubes 89 and 90 respectively. Thus, the embodiment shown in Figures 12 and 14 is self-adjusting and automatically maintains a fluid-tight seal between the inner and outer tubes 89 and 90 without the necessity for making periodic adjustments (as would be required in the embodiment shown in Figures 11 and 13).

In the embodiment shown in Figures 11 to 14 inclusive, the packing (125 or 135) is made in the form of a continuous and uninterrupted annulus as distinguished from the split ring 92 shown in Figures 4 and 5 and, thus, the possibility of leakage through the packing ring is further minimized.

In order to avoid accidental dis-assembly of the telescoped tubes 89 and 90, and to avoid possible injury to the packing ring 92, the upper margin of the outer tube 90 may be bent slightly inwardly as at 95, and a portion of the outer surface of the inner tube 89 immediately above the packing 92 may be pinched outwardly as at 96. Tube 90 is then prevented from sliding or being slid downwardly off of tube 89 by reason of the stop elements 95 and 96 coming into contact with each other. After the tubes 89 and 90 have been telescopically assembled, a cotter pin 97 may be inserted across the lower end of the outer tube 90, thereby preventing separation of the tubes 75

88 and 89 even when disassociated from the fitting 27.

The foregoing extensible telescopic inlet-stem arrangement is adjustable to fit drums or reservoirs of varying depths, thereby making possible the complete removal of all the contents of said drums or reservoirs.

In the embodiment illustrated in Figure 9 of the accompanying drawings, modified head and base fittings 98 and 99, stamped or pressed out of sheet-steel, are provided at the upper and lower ends of the pump barrel 25 (indicated in phantom fashion in dashed-dotted lines) in lieu of the cast fittings 26 and 27, respectively, of the first embodiment.

The head fitting 98 may be made up from a generally bell-shaped steel stamping or shell 100 having a circular side-opening 101 to the edges of which may be arc-welded the base of a discharge spout 102, which may be constructed from juxtaposed right and left oppositely-concave steel stampings which may be arc-welded together along their opposite meeting edges 103.

The lower portion of the head-fitting 100 is internally threaded at 104 for engagement with the upper end portion of the pump cylinder 25, and an internal annular shoulder 105 may be pressed out of the metal immediately above the screw-thread 104 for seating the sealing gasket 106.

At the uppermost end of the stamping 100, a central opening 107 is provided, into which extends the reduced lower end portion of a piston-rod bushing 108. This bushing 108 may be permanently secured to the stamping 100 by having its lowermost margin, which projects through the hole 107 into said stamping, crimped over the edge of said hole, as illustrated in Figure 9. The upper end portion of the passageway through the rod-guiding bushing 108 may be countersunk or reamed out as at 109, and annular packing means 43 may be forced downwardly against this conical reamed surface and crowded and guided thereby into intimate sealing contact with the reciprocable piston-rod 40 by means of the externally-knurled nut 44 which screw-threadedly engages the bushing 108.

The base-fitting 99 at the lower end of the pump cylinder 25 may be made up from two permanently-telescoped sheet-steel stampings 110 and 111. The outer stamping 110 is formed with polygonal seizure means 112 at its upper end, and may be drawn or pressed by suitable dies into three generally cylindrical or slightly tapered stepped zones 113, 114 and 115, of consecutively decreasing diameters, with annular shoulder portions connecting adjacent steps or zones. The inner surface of the largest-diameter zone 113 and the inwardly-extending annular shoulder at its lower end jointly afford a socket-like portion 60 into which may be permanently telescoped the upper zone 116 of the inner steel stamping 111. The next successively smaller zones 114 and 115 of the outer stamping 110 are each externally threaded, and are each adapted to be screwed into threaded drum bung-holes of corresponding diameters, as for example, into bung-holes of two-inch diameter and of one and one-half inch diameter, respectively. The metal at the bottom of the zone 116 of the inner stamping 65 extends radially inwardly to form an annular shoulder 117 on which may be seated the arrangement of annular sealing members 75 respectively disposed below and above the rim of the suction-valve body 76. The inner surface of the zone 116 is threaded for engagement with the lower end

portion of the pump cylinder 25, and when the assembled base-fitting 113 is tightly screwed onto the lower end of the cylinder 25, the sealing members 78 are operatively compressed between the lower end of the cylinder 25 and the juxtaposed shoulder 117, and the valve body 71 will be firmly held in position.

The central zone of the inner stamping 113 is depressed below the shoulder 117 sufficiently to provide room for the suction-valve body 71, with the side walls of said depressed zone and all other lower wall-portions of the inner stamping being spaced inwardly from the juxtaposed wall-portions of the outer stamping by some slight distance, to provide clearance therebetween. The very lowermost extremity of the inner stamping 113 is preferably downwardly flanged as at 118, and into the hole defined by this annular flange is screwed the upper threaded end of the fixed inlet-stem tube 89. The hole at the lower end of the outer stamping 110 is of at least slightly larger diameter than the outside diameter of the tube 89, thereby to provide a clearance space therebetween for a purpose which will presently appear.

Before the outer and inner stampings 110 and 113 are permanently press-fitted together, the inner surface of the outer stamping 110 and the outer surface of the inner stamping 113 preferably each have a similar groove 119 cut therein, extending from the upper end of the zones which are ultimately to be press-fitted together, downwardly to the other end of said zones, and when these stampings are finally permanently telescoped together, care is taken to see that these similar grooves 119 are in registration with each other. These registering grooves 119 together form a vent passageway which extends downwardly through the composite wall bounding the press-fit zone of the assembled stampings. The lower end of this vent passageway communicates with the clearance space between the lower portions of the outer and inner stampings 110 and 113, and this latter clearance space in turn communicates with the space inside the drum above the contained liquid. In this fashion, the space inside the drums above the liquid is vented, and sub-atmospheric pressures inside the drums are avoided.

In place of the grooves 119 cut in the stampings 110 and 113, as shown in Figure 9, I may provide the construction shown in Figure 10 for venting the space inside the drum above the liquid. In Figure 10 the inner and outer stampings 111 and 110 are shown dis-assembled. The inner stamping 111 has a vertical groove 128 cut therein—said groove being similar to the groove 119 shown in Figure 9 except that it terminates short of the upper end of the stamping 111. The outer stamping 110 has an opening 120 in the zone 113 thereof—said opening 120 being placed just below the polygonal edge 112.

When said outer and inner stampings 110 and 113 are permanently press-fitted together, care is taken to see that the groove 128 in the inner stamping 111 and the opening 120 in the outer stamping 110 are in registration with each other. Thus, the opening 120 and the groove 128 together form a vent passage-way extending from the side of the outer stamping 110 downwardly through the composite wall bounding the press-fit zone of the assembled stampings. The lower end of this vent passage-way communicates with the clearance space between the lower portions of the outer and inner stampings 110 and 113, and

this latter clearance space in turn communicates with the space inside the drum above the contained liquid, thereby venting said drum.

By use of the embodiment illustrated in Figure 10 the possibility of contaminating the contents of the drum (as for example by water) is minimized since the opening 120 extends horizontally rather than vertically when the pump is in use and since said opening 120 is more or less shielded by the overhang of the polygonal edge 112.

The present invention may be embodied in other specific forms without departing from the spirit or essential attributes thereof, and it is therefore desired that the present embodiments be considered in all respects as illustrative and not restrictive, reference being had to the appended claims rather than to the foregoing description to indicate the scope of the invention.

Having thus described the invention, what is hereby claimed as new and desired to be secured by Letters Patent, is:

1. In liquid-dispensing apparatus of the character described including a generally vertical pump cylinder, a fitting for the lower end of said cylinder having an internally-threaded upper mouth adapted screw-threadedly to receive the lower end of said cylinder, an internal annular shoulder below said mouth, the outer wall of said fitting bearing externally-threaded portions of successively decreasing diameters adapted for screw-threaded engagement with internally-threaded drum bung-openings of different diameters, an internally-threaded lower opening in said fitting spaced below said shoulder adapted screw-threadedly to receive the upper end of an inlet tube, and a suction-responsive check-valve housed in said fitting above said lower opening and arranged to permit flow of liquid therethrough solely in an upward direction, said check-valve housing having a rim portion extending over said internal annular shoulder adapted to be caught between said shoulder and the juxtaposed lower end of the pump cylinder when the latter has been operatively screwed into the mouth of said fitting.

2. In liquid-dispensing apparatus of the character described, operable to dispense the liquid contents of storage drums or the like, and including a generally upright pump cylinder adapted to extend exteriorly of said drum and an inlet tube adapted to extend into the interior of said drum, a base fitting for said cylinder having a plurality of different-diametered externally-threaded stepped cylindrical portions adapted snugly to be screwed into different-diametered bung-openings of said drums, an internally-threaded opening at the upper end of said base fitting into which may be screwed the lower end of said pump cylinder, an inwardly-extending horizontal annular shoulder at the lower end of said internally-threaded upper opening, polygonal seizure-means on the outer surface of said fitting adapted for engagement with a turning tool, an internally-threaded hole in the lower portion of said fitting adapted screw-threadedly to receive the upper end of said inlet tube, and a vent passageway through the wall of said fitting communicating at its upper end with the atmosphere and having its lower end adapted for free communication with the space inside said drum above the contained liquid when said apparatus is operatively engaged with said drum.

3. In apparatus adapted for dispensing the liquid contents of storage drums or the like having internally-threaded bung-openings, a fitting

engageable with said bung-openings comprising two telescoped annular steel-stampings, the outer stamping bearing polygonal seizure-means adapted for engagement with a turning tool, and having externally-threaded lower end portions of varying diameters adapted for screw-threaded engagement with internally-threaded bung-openings of varying diameters, the inner stamping having its upper portion press-fitted into the upper mouth of said outer stamping, said upper portion of the inner stamping being internally-threaded, an annular inwardly-extending shoulder portion at the base of said internally-threaded upper portion, and an internally-threaded hole at the lower end of said inner stamping, and a vent passageway extending downwardly through the press-fit zone intermediate the assembled inner and outer stampings, said passageway being formed by registering juxtaposed grooves in the outer surface of the inner stamping and the inner surface of the outer stamping, the upper end of said passageway communicating with the atmosphere and the lower end thereof being adapted for communication with the space in said drum above the contained liquid when said fitting is operatively screwed into said bung-opening.

4. An apparatus adapted for dispensing the liquid contents of storage drums or the like having internally-threaded bung-openings, a fitting engageable with said bung-openings comprising two telescoped annular steel-stampings, the outer stamping bearing polygonal seizure-means adapted for engagement with a turning-tool, and having an externally-threaded lower end portion adapted for screw-threaded engagement with a corresponding internally-threaded bung-opening, the inner stamping having its outer portion press-fitted into the upper mouth of said upper fitting, said upper portion of the inner stamping being internally-threaded, and an annular, inwardly-extending shoulder portion, an internally-threaded upper portion, an internally-threaded hole at the lower end of said inner stamping, and a vent-passageway extending downwardly through the press-fit zone intermediate the assembled inner and outer stampings, said passageway being formed by registering a groove in the outer surface of the inner stamping with an opening passing through the side wall of said outer stamping

5 the upper end of said passage-way communicating with the atmosphere and the lower end of said passage-way being adapted for a communication with the space in said drums or the like above the contained liquid when said fitting is operatively screwed into said bung-openings.

10 5. In a liquid-dispensing apparatus adapted for operative connection with a liquid-containing drum or the like having an internally-threaded bung opening, said apparatus being thereafter operable to dispense the liquid therefrom, a generally vertical pump-cylinder, a valved lift-piston slidably mounted inside said cylinder, means for operating said lift-piston, a base-fitting of sheet-metal or the like screw-threadedly connected to the lower end of said pump-cylinder and adapted to be screwed tightly into said internally-threaded bung opening, said sheet-metal base-fitting having a plurality of different-dia metered inner bores separated by a transversely-extending annular shoulder and having a plurality of different-dia metered cylinder portions having external screw-threads formed thereon, whereby said apparatus may be operatively connected to drums having different-dia metered bung-openings, and a spring-pressed check valve operatively mounted within said base-fitting and peripherally supported by said transversely-extending annular shoulder, said check-valve being held against displacement by the lower end of said cylinder.

20 30 6. In a liquid-dispensing apparatus having a generally vertical pump-cylinder and a lift-piston slidably mounted within said cylinder, a base-fitting of sheet-metal or the like screw-threadedly connected to the lower end of said pump-cylinder, said base-fitting having a plurality of different-dia metered inner bores separated by a transversely-extending annular shoulder, and having a plurality of different-dia metered cylindrical portions having external screw-threads formed thereon, whereby said apparatus may be operatively connected to drums having different-dia metered bung-openings, and a spring-pressed check valve operatively mounted within said base-fitting and peripherally supported by said transversely-extending annular shoulder, said check-valve being held against displacement by the lower end of said cylinder.
